UNITED STATES PATENT OFFICE.

KINSEY LANIUS, OF DENVER, COLORADO, ASSIGNOR, BY MESNE ASSIGNMENTS, TO EDITH ROSCOE, OF PHILADELPHIA, PENNSYLVANIA.

AMALGAMATOR AND CONCENTRATOR.

SPECIFICATION forming part of Letters Patent No. 755,230, dated March 22, 1904.

Application filed July 7, 1902. Serial No. 114,652. (No model.)

To all whom it may concern:

Be it known that I, KINSEY LANIUS, a citizen of the United States, residing at Denver, in the county of Arapahoe and State of Colorado, have invented certain new and useful Improvements in Amalgamators and Concentrators, of which the following is a specification.

This invention relates to amalgamators and concentrators for extracting gold and silver from ores.

The object of this invention is to provide an amalgamator and concentrator which will include an amalgamating-trough provided with removable guards adapted to be locked therein and screen-sections which will discharge fine particles of gold into lower amalgamating, reciprocating, concentrating and arrastra troughs, the upper and lower troughs having their outlets at opposite ends and inclined in opposite directions, the arrastra being located between amalgamating reservoirs or pans, the said arrastra serving to brighten and separate such gold from the dross which cannot be readily separated in the amalgamating-trough, and a fixed frame carrying a series of fingers extending down in the amalgamating-pans, adapted to keep the mercury-baths therein in a state of agitation.

A further purpose of the invention is to construct a machine of the character described in a simple, light, and durable manner, and to provide mechanism for imparting end movement to the troughs simultaneously with a jerking or jarring motion.

In brief, my invention consists in certain novel features, the particular construction of the various parts, and in the arrangement and combination of said parts, all of which will be hereinafter fully described, and specifically pointed out in the appended claims, which are intended to accord in their terms, spirit, and meaning with the prior state of the art and the existing laws.

In the drawings forming a part of this specification, Figure 1 is a view in side elevation. Fig. 2 is a top plan view, parts being broken away. Fig. 3 is a vertical longitudinal sec-

tional view. Fig. 4 is a horizontal sectional view. Fig. 5 is a vertical transverse sectional view looking in one direction. Fig. 6 is a vertical transverse sectional view looking in the other direction. Fig. 7 is a detail view of the screen, illustrating the manner in which it is locked upon the frame. Fig. 8 is an enlarged detail view of the ball-bearing sleeve.

The main frame A of the machine is preferably made of tubular material in the interest of lightness and is ordinarily rectangular in its general contour, comprising parallel upper side sections 1, lower side sections 2, vertical corner-sections 3, connecting the upper and the lower sections, upper end sections 4, and lower end sections 5, connecting the upper, lower, and corner sections, as shown in Fig. 1. Between the lower side sections are pivoted two shafts 6, carrying angular levers 7, having mounted upon one end of each a wheel 8, the other ends being connected by parallel rods 9. One of these levers is connected by a rod 10 to a lever 11, mounted upon one of the corner-sections and provided with a suitable device for locking it in a depressed position, thus providing means whereby the frame may be easily raised upon the wheels and readily conveyed from place to place.

Within the main frame an auxiliary frame B is mounted to swing upon rods 12. The auxiliary frame B is similar in construction to the main frame, being usually rectangular and of less dimensions than the dimensions of the compartment of the main frame in which it is placed, as shown in the several figures. This auxiliary frame B consists of upper and lower end sections 13, upper and lower side sections 14, and upright end sections 15, together with oppositely-disposed angular sections consisting of an upper and lower rods 16 and 16', held or braced together at their free end by a plate 18, the rods 16 and 16' having mounted thereupon sliding tops 19 and 19', the purpose of which will be hereinafter described.

The auxiliary frame B carries an amalgamating-trough C at its upper portion, mounted upon the adjustable brackets 20, adapted to

slide up or down on the upright end sections 15. This amalgamating-trough consists of a frame having upper and lower side sections 21, upright sections 22, connecting the upper 5 and lower sections, end sections 23, connecting the side sections, and transverse sections 24, connecting the lower side sections. This frame is adapted to receive and support the trough proper, which is provided approximately 10 near its open end with a strip 25 and perforated above the strip, as shown at 26, so as to form a screen. It is also provided with a screen 27, which is supported over the screen 26 by the strip 25. These screens extend from 15 side to side of the trough and permit the fine particles of gold and fine ore which sifts through the openings in the guard E, to be hereinafter described, to pass down and out from the amalgamating-trough into a lower 20 trough D, also to be hereinafter described, the coarse material in the amalgamating-trough C finding an exit at the lower or open end of said trough. This trough is further provided with a guard E, consisting of a series of steel strips 25 28, so shaped as to form inverted troughs, which are connected by transverse strips 29, bent so as to lock the parts together. This guard is formed in two parts adapted to rest in the bottom of the trough and to be locked 30 therein by the rod 30, which extends across the trough and is adapted to be held in place by a lock 31. This guard has two functions, one of which is to receive and carry off the coarse material and the other is to prevent 35 the amalgam from being stolen from the trough.

It will be observed that by adjusting the supports or brackets 20, which may be fixed in position by suitable set-screws, the inclination 40 of the amalgamating-trough may be increased or decreased, as occasion may demand. The inner surface of the amalgamating-trough C is coated with mercury or otherwise treated for the purpose of causing the gold to adhere 45 thereto and separate itself from the dross or crushed ore.

Below the amalgamating-trough C is a concentrating-trough D, which trough is inclined in an opposite direction from the upper or 50 amalgamating trough, and the outlet of the concentrating-trough is at that end which is beneath the inlet portion of the amalgamating-trough. The concentrating-trough is likewise supported by adjustable brackets 32, 55 adapted to increase or decrease the inclination, as occasion may demand, this trough consisting of a frame having upper and lower side sections 33, connected by upright sections 34, upper and lower end sections 35, connecting 60 the upper and lower side sections, and transverse sections 36, connecting the lower side sections. This frame supports the trough proper, which is provided with three amalgamating pans or reservoirs 37, 38, and 39, 65 which are formed therein by suitable parti-

tions, each pan being provided with a drain-plug 40 for the purpose of drawing off the mercury.

The reservoirs or pans 37, 38, and 39 are adapted to receive a mercury-bath and are 70 likewise adapted to receive suitably-applied electric currents, as plainly shown in Fig. 3, wherein *a* indicates the negative wire, and *b* the positive wire. At the receiving end of the concentrating-trough is a pivoted gate 41, 75 which may be opened or closed, as occasion may demand, so as to pass out the concentrates or force them to go through the amalgamating reservoirs or pans; also, an inclined directing-plate 42, adapted to receive the material which passes through the screens in the amalgamating-trough C and direct it to the center amalgamating-pan 38. Between the amalgamating-pans 37 and 38 is located an arrastra F, consisting of two blocks of stone, 85 glass, or the like, (designated, respectively, as 43 and 44. The lower block 43 is secured to the bottom of the trough D, while the upper block 44 is secured by means of adjustable rods 45 and 46 to a shaft 47, which is 90 mounted between oppositely-disposed angular levers 48, pivoted upon the sides of a frame G, hereinafter fully-described, the free ends of the levers engaging the lugs 49 upon the frame of the concentrating-trough D for the 95 purpose of giving a vertical motion to one end of the upper block when the auxiliary frame carrying said trough is swung back and forth.

As the concentrating-trough moves with the suspended or auxiliary frame B, the lower 100 block 43 of the arrastra will be laterally reciprocated beneath the upper block 44. These blocks are one of the main features of my invention, as the gold which cannot be readily separated by the amalgamating trough and 105 reservoirs or pans and by the action of suitably-applied electric currents will float up between the stones or blocks and will there be ground and separated from the dross and so polished or brightened that it will adhere to 110 the mercury.

The frame G, consisting of side sections 50, connected by end sections 51, is mounted upon adjustable brackets 52 upon the stationary frame A. This frame is provided with transverse sections 53, connecting the side sections 50 and adapted to support corresponding plates 54, provided with a series of aluminium fingers 55, the lower ends of which are bent, so as to form paddles, which paddles extend 115 down into the amalgamating reservoirs or pans 37 and 38 and serve to keep the mercury-baths in said pans in a state of agitation while the machine is being operated.

Over the frame G is located a screen H, 120 which is supported upon the brackets 52 and locked upon the frame by a rod 56, which extends beneath said frame and is provided with a lock 57. This screen covers the entire frame 125 and projects over the ends and sides of the 130

concentrating-trough, thus rendering it impossible to steal the amalgam and quicksilver therefrom.

The auxiliary or suspended frame B is given 5 end motion through the medium of cams 58, which are mounted on a transverse shaft 59, journaled upon the end uprights of the stationary frame A, said shaft being driven by a pulley 60. These cams consist of disks 10 having corresponding ball-bearing sleeves 61, adapted to engage the adjustable stops 19 or 19' alternately. The object in having these stops adjustable is to provide means for reversing the motion of the machine, which may 15 be accomplished by adjusting one set of the stops so that they will be brought in contact with the revolving sleeves and the others out of the line of contact, and vice versa, the bottom portion of the auxiliary frame being connected by a tension device with the bottom portion of the main frame A, and these tension devices are so placed that when the auxiliary frame is forced to move in one direction by the cams and is released by said cams 20 the tension devices serve to return the auxiliary frame to its normal position. These tension devices, as shown, consist of cylinders 62, adapted for attachment to either end of the main frame at opposite sides, and a spring-controlled plunger 63, having movement in 25 said cylinder, the outer end of the plunger being connected by a rod 64 to an angular lever 65, pivoted upon the bottom side section of the auxiliary frame and adapted to be held 30 in a depressed position by the lugs 66 or 67, as occasion may demand, these tension devices being adjustable, so as to give the desired strength to the jerking or jarring motion and to register the number of pounds required to the jerk or jar to work the ore. 35

Having thus described the various features of my invention, what I claim as new, and desire to secure by Letters Patent, is—

1. In an amalgamator and concentrator, a 45 trough having reservoirs for mercury-baths, an arrastra located between the reservoirs, which arrastra consists of a fixed and a movable block, one adapted to slide over the other, one end of the movable block having a vertical movement, substantially as specified.

2. In an amalgamator and concentrator, an amalgamating and concentrating trough provided with reservoirs, an arrastra located between the reservoirs, which arrastra consists 55 of a fixed and a movable block, the movable block being adjustably connected to a rocking shaft, the said rocking shaft adapted to impart a vertical movement to one end of the movable block, the movable block adapted to slide over the fixed block, substantially as specified.

3. In an amalgamator and concentrator, an amalgamating and concentrating trough provided with reservoirs, drain-plugs in the said 60 reservoirs, a fixed frame located over the said

amalgamating and concentrating trough, plates upon the said frame carrying a series of fingers which extend down into the said reservoirs, an arrastra located between the said reservoirs, which arrastra consists of a 70 block fixed in the bottom of the trough, and a movable block adjustably connected by rods to a rocking shaft, the said rocking shaft adapted to impart a vertical movement to one end of the movable block, and means for imparting a jerking or jarring motion to the said trough, substantially as specified. 75

4. In an amalgamator and concentrator, an amalgamating and concentrating trough having reservoirs therein, a fixed frame located 80 over the trough having plates thereupon carrying a series of fingers which extend down into the reservoirs, an arrastra located between the reservoirs, which arrastra consists of a block secured in the bottom of the trough, 85 and a block connected by adjustable rods to a rocking shaft, the said shaft mounted between angular levers upon a fixed frame, lugs upon the trough for engaging the levers, and means for imparting a jerking or jarring motion to the said trough, substantially as specified. 90

5. In an amalgamator and concentrator, an amalgamating and concentrating trough mounted upon adjustable brackets, reservoirs 95 located within said trough, drain-plugs in the reservoirs, a frame located over the trough upon adjustable brackets, plates secured to the frame, fingers extending from the plates into the reservoirs, an arrastra located between the reservoirs, the arrastra consisting of two blocks, one of which is secured to the trough, the other having adjustable rods by which it is secured to a rocking shaft, the said shaft mounted upon the frame, arms 100 upon the shaft for engaging lugs upon the trough, a screen covering the said trough and frame, a rod for locking the screen to the frame, and means for reciprocating the said troughs, substantially as specified. 105

6. In an amalgamator and concentrator, a main frame, a vibratory frame located within the main frame, an upper amalgamating-trough and a lower amalgamating and concentrating trough carried by the vibratory frame, 110 reservoirs carried in the amalgamating and concentrating trough, agitating-fingers carried by plates secured to a frame mounted upon adjustable brackets on the main frame and extending into the reservoirs carried by the concentrating-trough, and an arrastra located between the reservoirs in the concentrating-trough, consisting of two blocks, one fixed to the bottom of the amalgamating and concentrating trough, and the other adjustably 115 secured to a rocking shaft mounted between levers upon the adjustable frame, substantially as specified.

7. In an amalgamator and concentrator, a main frame, a frame mounted to swing in the 120

125

130

main frame, an upper amalgamating-trough and a lower amalgamating and concentrating trough, adjustably mounted upon and carried by the said swinging frame, screens in the amalgamating-trough through which the gold and fine ore pass, a removable guard in the trough with means for locking the same in position, an adjustable frame mounted on the main frame between the troughs, plates upon the adjustable frame, agitating-fingers carried by the said plates extending into reservoirs in the concentrating-trough, drain-plugs in the reservoirs, a pivoted gate in one end of the concentrating-trough, a deflecting-plate in the concentrating-trough, a screen covering the said concentrating-trough and adjustable frame, and means for imparting motion to the swinging frame, substantially as specified.

8. In an amalgamator and concentrator, a main frame, a vibratory frame located within the main frame, arms upon the vibratory frame, adjustable stops mounted upon said arms, an upper amalgamating-trough and a lower amalgamating and concentrating trough carried by the said vibratory frame, a frame adjustably mounted upon the main frame, plates upon the adjustably-mounted frame, agitating-fingers upon the plates, reservoirs in the amalgamating and concentrating trough adapted to receive the fingers, an arrastra located between the reservoirs, a screen covering the adjustably-mounted frame and amalgamating and concentrating trough, a driving-shaft, a support for the said shaft, cams located on the shaft, arranged for engagement with the said adjustable stops, and tension devices connecting the main frame with the vibratory frame, substantially as specified.

9. In an amalgamator and concentrator, a main frame, a frame mounted to swing in the main frame, tension devices connecting the main frame with the swinging frame, the said device controlling the movement of the swinging frame in one direction, arms upon the swinging frame, adjustable stops upon the said arms, a driving-shaft carried by the main frame, disks upon the driving-shaft, revolving sleeves upon the disks adapted to engage the adjustable stops for imparting motion to the swinging frame, an amalgamating-trough provided with screens in its bottom at a point in its length, a removable guard with means for locking the same in the amalgamating-trough, the amalgamating-trough being supported in the swinging frame, and an amalgamating and concentrating trough also mounted in the swinging frame below the amalgamating-trough, the receiving end of the amalgamating and concentrating trough being below the screens in the amalgamating-trough, reservoirs located in the amalgamating and concentrating trough, adapted to receive mercury-baths, a frame adjustably mounted upon the main frame, plates upon the adjustably-mounted frame, fingers upon the plates extending

into the said reservoirs, an arrastra located between the said reservoirs, comprising a block secured to the amalgamating and concentrating trough and a second or upper block adjustably connected to a rocking shaft secured between levers pivoted to the adjustably-mounted frame, the said levers adapted to engage lugs upon the sides of the amalgamating and concentrating trough, and a screen covering the said amalgamating and concentrating trough and adjustably-mounted frame, substantially as specified.

10. In an amalgamator and concentrator, a main frame, wheels upon the frame, means for raising or lowering the wheels, an auxiliary frame mounted to swing in the main frame, an inclined amalgamating-trough adjustably supported in the swinging frame, and provided with screens and a guard in its bottom, an amalgamating and concentrating trough also adjustably supported in the swinging frame below the amalgamating-trough, the amalgamating and concentrating trough being inclined in an opposite direction to the amalgamating-trough, a driving mechanism for imparting end motion to the swinging frame, tension devices connecting the main frame to the swinging frame, which tension devices are adjustable, reservoirs located in the amalgamating and concentrating trough, a frame adjustably mounted upon the main frame, plates upon the adjustably-mounted frame, fingers upon the said plates, which fingers extend into the said reservoirs, an arrastra located between the said reservoirs, which arrastra comprises a block secured in the amalgamating and concentrating trough and another block adjustably secured to a shaft mounted between levers, said levers pivoted to the adjustably-mounted frame, lugs upon the amalgamating and concentrating trough, adapted to engage the free ends of the levers, and a screen covering the said adjustably-mounted frame and amalgamating and concentrating trough, substantially as specified.

11. In an amalgamator and concentrator, a main frame, wheels upon the frame, means for raising and lowering the wheels, an auxiliary frame mounted to swing in the main frame, an inclined amalgamating-trough adjustably supported in the swinging frame, screens in the bottom of the said trough, a guard covering the bottom of the amalgamating-trough, with means for locking the same within the trough, an amalgamating and concentrating trough also adjustably supported in the swinging frame, below the amalgamating-trough, the amalgamating and concentrating trough being inclined in an opposite direction to the amalgamating-trough, a pivoted gate at the elevated end of the amalgamating and concentrating trough, a deflecting-plate in the elevated end of the amalgamating and concentrating trough, and reservoirs in the amalgamating and concentrating trough, a frame ad-

justably mounted in the main frame having plates secured thereto, fingers upon the plates extending into the reservoirs, an arrastra located between the reservoirs, comprising a 5 lower block secured in the amalgamating and concentrating trough, and an upper block, adjustably connected to a shaft mounted between levers pivoted to the frame supporting the fingers, the said blocks adapted to rub together, tension connections between the main

frame and swinging frame, and a driving-shaft mounted on the main frame, disks upon the shaft, revolving sleeves upon the disks, adapted to engage adjustable stops upon the swinging frame, substantially as specified. 15
